Primary Examiner — Cynthia Ramirez*Assistant Examiner* — Michael A Maharajh(74) *Attorney, Agent, or Firm* — Preston P. Frischknecht;
Project CIP(57) **CLAIM**The ornamental design for a pain management device, as
shown.**DESCRIPTION**

FIG. 1 is a front perspective view of a pain management device, showing our new design;

FIG. 2 is a rear perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of
illustrating portions of the pain management device, which
form no part of the claimed design.**1 Claim, 7 Drawing Sheets**---
